UNITED STATES PATENT OFFICE.

RICHARD H. BRIGGS AND JAMES H. DOUGHERTY, OF WHISTLER, ALA.

MECHANISM FOR MAKING LADDER-IRONS AND HAND-HOLDS FOR FREIGHT-CARS.

SPECIFICATION forming part of Letters Patent No. 223,877, dated January 27, 1880.

Application filed September 12, 1879.

To all whom it may concern:

Be it known that we, RICHARD H. BRIGGS and JAMES H. DOUGHERTY, of Whistler, in the county of Mobile and State of Alabama, 5 have invented new and useful Improvements in Mechanism for Making Ladder-Irons and Hand-Holds for Freight-Cars, of which the following is a specification.

Figure 1 is a plan of the devices. Fig. 2 is 10 a cross-sectional elevation on line $x-x$, Fig. 1. Fig. 3 is a cross-sectional elevation of a portion of the machine on line $y-y$, Fig. 1. Fig. 4 is a cross-sectional elevation of a portion of the machine on line $z-z$, Fig. 1. Fig. 5 is a 15 perspective view of a hand-hold iron as made by the machine. Fig. 6 is a perspective view of a ladder-iron as made by the machine. Fig. 7 is a front elevation of the devices.

Similar letters of reference indicate corresponding parts.

The object of this invention is to provide new and simple devices for making freight-car ladder-irons and hand-holds.

In the drawings, A represents the base, bolted 25 on which, at one end, is a slotted gaged upright, B, provided with a sliding step or gage, C. The two standards D D, set on the base A, support a horizontal frame, E, that carries on one end a fixed clamp-jaw, F, and a movable clamp-jaw, F', between the grooved faces 30 of which is space enough for the admission of the iron rod to be operated upon. The movable clamp-jaw F' slides transversely in the end of the frame E, and is provided with a 35 socket, a', in which engages the rounded end of the dog G. This dog G is rigidly secured on the end of the rocking shaft H, which is supported in a horizontal position under the frame E by the hangers I and J, that are secured 40 to the under side of the frame E.

A lever, K, fixed to the main end of this 45 rocking shaft H, and held up by the spiral spring S', is connected with the foot-lever L by the rod M, and the fixed end of this lever L is pivoted in the lug N, that is fastened to the base A. Embedded in a raised boss or anvil, O, on the upper surface of the frame E is a circular die, P. Firmly fixed upon the frame E, over the clamp-jaw F', is an upwardly-projecting curved arm, Q, provided with a socket, b', and fitted movably in this socket b' is a die, R, that is held just above the space between the clamp-jaws F and F'.

Fixed on the top of the frame E, and about midway of its length, is a raised bent standard, 55 S, and centrally in front of this standard S is fixed on the frame E a plate, T, having on one end a vertical guiding socket or tube, U, for guiding the punch V, to which are connected the levers W W W, that are fulcrumed in the lugs c' c' of the standard S. Under the base of this standard S, and extending through under the punch V, is a horizontal aperture, X.

On the opposite end of the frame E from the clamp-jaws F and F' are the bending devices, and these consist of two like horizontal spring-gages, A' A', that are composed of metallic rods d' d', encircled with spiral springs f' f', said rods d' d' being provided on their outer ends with nuts g' g', and on their inner 70 ends with beveled blocks h' h', and these gages A' A' are horizontally movable in the arms i' i' and standards B' B'. Pivoted between these standards B' B', above the gages A' A', is the bending-lever O', that moves in a vertical plane, 75 and pivoted to a raised ledge, k', on the frame E, in rear of the standards B' B', is the bending-lever D', that moves in a horizontal plane. In this ledge k', centrally in front of the space between the standards B' B', is an opening, l', 80 through which the bar of iron may be introduced for bending.

The lever D' can be adjusted as shown in Fig. 1, or be reversed and pivoted in the hole m' on the opposite side of the opening l'.

The devices are operated as follows: The iron bar or rod, after being heated, is set with one end between the clamp-jaws F and F' and the other end resting on the step or gage C. The foot or other power is then applied to the lever L, which causes the clamp-jaw F' to close upon the rod and grip it tightly; then one or more blows from a sledge on the die R upset the end of the rod. The upset end of the rod is then placed in the circular die P, when two 95 or more blows of a sledge flatten it. It is then inserted into the aperture X until its flattened end reaches under the punch V, where a hole is punched in it by power applied to the levers W W W. The rod is then withdrawn 100 and taken to the bending device, the lever C' of which is kept in an upright position by the

spring-gages A' A', and inserted through the opening l' until it touches the spring-gage A' A'. The lever D' is then forced around against the rod and bends it at a right angle, making the bend shown upon the hand-hold at m'', Fig. 5, and while the lever D' holds the rod in this position the lever C' is brought down, forming the last bend, (seen at n'', Fig. 5.)

The above is the operation for fashioning one end of the hand-hold. The opposite end is fashioned in the same manner, and the hand-hold can be finished in one heat.

In Fig. 6 is shown a section of a ladder-iron made by this machine, the operation of the machine being the same in both cases, only that but one bend is made in each end of the ladder-iron.

With this mechanism we have made one thousand ladder-irons in ten hours, and we know of no mechanism constructed for this

purpose that is so efficient, so durable, or so accurate in its performance.

Having thus fully described our invention, we claim as new and desire to secure by Letters Patent—

1. The combination, with frame E, of the spring-gages A', the bending-levers C' D', and the raised ledges k', having the opening l', as and for the purpose specified.

2. The frame E, provided with the series of devices herein described for upsetting, flattening, punching, and bending the metal rod, all relatively arranged and operating as set forth.

RICHARD HENRY BRIGGS.
JAMES HENRY DOUGHERTY.
